UNITED STATES PATENT OFFICE.

MARK FRED RICHARDSON, OF LEONIA, NEW JERSEY.

DOOR-LOCK.

1,120,538.

Specification of Letters Patent.

Patented Dec. 8, 1914.

Application filed January 30, 1914. Serial No. 815,505.

To all whom it may concern:

Be it known that I, MARK F. RICHARDSON, a citizen of the United States, and a resident of Leonia, in the county of Bergen and State of New Jersey, have invented a new and Improved Door-Lock, of which the following is a full, clear, and exact description.

The object of the invention is to provide a new and improved door lock arranged normally to hold the door securely locked against accidental opening and permitting of unlocking the door from one face thereof by pressure applied in a transverse direction instead of turning a door knob or the like, and to allow unlocking from the other face of the door on pulling the door knob.

In order to accomplish the desired result use is made of a bolt mounted to swing into and out of locking position relative to the keeper in the door jamb, a locking lever normally engaging the said bolt to hold the latter in locking position, and manually controlled actuating means on each face of the door and adapted to impart a swinging motion to the said locking lever to unlock the said bolt.

A practical embodiment of the invention is represented in the accompanying drawings forming a part of this specification, in which similar characters of reference indicate corresponding parts in all the views.

Figure 1 is a sectional side elevation of the door lock as applied, the section being on the line 1-1 of Fig. 2; Fig. 2 is a sectional view of the same on the line 2-2 of Fig. 1; Fig. 3 is a similar view of the same with the door partly open; Fig. 4 is a transverse section of the same on the line 4-4 of Fig. 2; Fig. 5 is a sectional view of the same with the parts in position after the door is swung open; Fig. 6 is a sectional view of the means for locking the actuating plate against movement, the section being on the line 6-6 of Fig. 4; Fig. 7 is a sectional side elevation of the same; Fig. 8 is a sectional view of the keeper and the bolt-actuating means mounted therein, the section being on the line 8-8 of Fig. 1. Fig. 9 is a side elevation partly in section of the door lock provided with a key-controlled mechanism for locking the knob against sliding movement; and Fig. 10 is a sectional view of the same on the line 10-10 of Fig. 9.

The door A is provided with a mortise for the reception of the lock casing B in which is mounted a vertically-disposed pivot C'

carrying a bolt C adapted to engage with its free end a keeper D held in a mortise in the door jamb E. The bolt C is provided on the top and bottom and forward of the pivot C' with cams C² adapted to be engaged by sidewise-extending pins F held on arms F' fulcrumed at F² on the keeper D and extending within the mortise of the door jamb E. Springs F³ held on the keeper D press the free ends of the arms F' to normally hold the latter and consequently the pins F in outermost position so that the pins F project into the path of the cams C² when the door A is swung into closed position. The inward movement of the arms F is limited by stops D' arranged on the keeper D.

The bolt C is engaged by a retractile spring C³ attached to the casing B and the said bolt C is provided opposite the pivot C' with an offset C⁴ adapted to be engaged by one end of a lever G mounted to swing on a vertical pivot G' arranged within the casing B. The other end of the lever G is pressed on by a spring G² held in the casing B and the said end is engaged by a member H' in the form of a plate extending transversely through the back of the lock casing B and through the door A beyond the inner face thereof, as plainly indicated in Figs. 2, 3, 4 and 5. The member or plate H' is attached to the inner face of a plate or arm H fulcrumed at its lower end at H² on the outer face of the door A, as plainly shown in Fig. 4, and the upper end of the said arm H is pressed on by a spring H³ interposed between the outer face of the door and the arm H, thus holding the arm H normally in an outward position, as shown in Fig. 4, and thereby allowing the lever G to engage the bolt C and its lug C⁴ with a view to lock the bolt C in locking position, that is, at the time it engages the keeper D. The outward swinging movement of the arm is limited by a suitable stop H⁴ held on the door A (see Fig. 4), and the arm H is preferably provided with a handle H⁵ adapted to be taken hold of by the user.

When the door is locked as shown in Figs. 1 and 2 and a person exerts pressure on the arm H and swings the same inward toward the face of the door, then the plate H' imparts a swinging motion to the locking lever G whereby the latter swings out of engagement with the bolt C, thus releasing the latter and allowing the same to swing laterally by the action of its spring C³. As soon

as the bolt C is released the pressure exerted on the arm H causes the door A to swing open. It is understood that when the bolt C is released it swings laterally so that its outer face is flush with the outer edge of the lock casing B (see Fig. 5). When the door is now swung shut the pins F engage the cams C² whereby an outward swinging movement is given to the bolt C so that the latter 5 swings into the keeper D, and as the pressure on the locking lever G is now released it is evident that the lever G reengages the bolt C at the offset C⁴ thus holding the bolt C in locking position, as shown in Figs. 1 10 and 2.

In order to permit opening of the door from the inner face thereof, the following arrangement is made: The inner end of the lever G is engaged by a lug I' projecting 15 sideways from a block I mounted to slide transversely in a suitable bearing B' arranged in the casing B. The inner end of the spindle J' of the door knob J is secured to the said block I, as plainly indicated 20 in Fig. 2, and the shank of the said door knob J is mounted to slide in a suitable escutcheon K attached to the inner face of the door A. The knob J is provided at its shank with a pin J² engaging 25 a slot K' in the escutcheon K (see Figs. 4 and 10) to prevent the door knob J from being turned. Now when the several parts are in locked position, as shown in Figs. 1 30 and 2, and a person pulls on the knob J then an inward sliding movement is given 35 to the block I which by the lug I' imparts a swinging motion to the locking lever G so that the latter releases the bolt C to allow the door to swing open by the pull exerted 40 on the knob J.

From the foregoing it will be seen that by the arrangement described the door when 45 swung shut is locked in closed position by the bolt C swinging into engagement with the keeper D thus holding the door against accidental opening. When it is desired to open the door from the outside then it is only necessary to exert pressure on the arm H whereby the bolt C is unlocked as previously explained and the door is swung 50 open by the exertion of the pressure on the arm H. In case the locked door is to be opened from the inside it is only necessary for a person to pull on the knob J whereby the bolt C becomes released and the door swings open by the pull exerted on the knob J.

As shown in the drawings, the plate H is mounted on the outer face of the door A and 60 the knob J is located on the inner face of the door, but it is evident that the positions of the plate H and the knob J can be reversed. Thus for inward swinging doors, such as are used in dwellings, the arrangement is as shown in the drawings, and for

outward swinging doors, such as are used in schools, theaters and other public buildings the positions of the plate H and the knob J are reversed, as shown in Figs. 9 70 and 10.

The plate H' and the arm H may be locked against movement and for this purpose the plate H' is provided with an aperture H⁶ (see Fig. 4) adapted to be engaged by a pin L' held on the lower end of an arm L fulcrumed at its upper end at L² in the casing B, as plainly shown in Figs. 4 75 and 7. The arm L is provided with a transverse rod L³ extending through a slot B² in the front of the lock casing B, see Fig. 80 6, and the forward end of the pin L³ is engaged by the head N' of a sliding catch N mounted to slide in a suitable casing N² secured to the inner face of the door A, as plainly shown in Figs. 4 and 6. Normally 85 the pin L' is out of engagement with the aperture H⁶, but when it is desired to lock the plate H' and the arm H against movement then the operator slides the catch N from the left to the right so as to impart 90 a swinging motion to the arm L with a view to engage the pin L' with the aperture H⁶, thus locking the plate H' against transverse movement. It is understood that the locking of the plate H' and the arm H does 95 not interfere with the actuating of the lever G on pulling of the knob J as the knob movement and the movement of the arm H are wholly independent one of the other.

The arm L is controlled by a key O adapted to be inserted in a keyhole formed in the plate H, the outer face of the door A and the casing B, the bit of the key being adapted to engage a lug L⁴ on the arm L (see Figs. 1, 4 and 7). By the insertion of 100 the key O and turning it, the arm L is swung out of engagement with the plate H', thus allowing opening of the door from the outside on subsequently pressing the plate H toward the door A. 105

In case the door swings outward and the positions of the arm H and the knob J are reversed, as shown in Figs. 9 and 10, then use is made of a key-controlled locking device for the knob J, and for this purpose use is made of a vertical arm P pivoted at its upper end at P' on the lock casing B and the said arm is adapted to engage a notch I² formed in the block I to hold the block 115 against transverse movement. The arm P is provided with a knob or handle P² extending through slots in the casing B and the door A to the inner face thereof, the handle P² being guided in a suitable guide-way Q held on the inner face of the door A. By the arrangement described the door can be locked against opening from the outside on pulling the knob J, by the user manipulating the handle P² to engage the arm P with the notch I². The arm P is 120 125 130

- adapted to be swung into unlocking position relatively to the block I by the use of a key R adapted to be inserted into a key-hole of a keyhole plate S attached to the door at the outer face thereof. Now when the arm P is moved into locking position relatively to the block I by a person manipulating the handle P² as above described, the door cannot be unlocked by a person pulling 10 on the knob J, but a person on inserting a key R and turning the same causes the arm P to swing out of locking engagement with the block I to allow opening of the door on a subsequent pull on the door knob 15 J, as above described.
- The door lock shown and described is very simple and durable in construction and its parts are not easily liable to get out of order.
- Having thus described my invention, I claim as new and desire to secure by Letters Patent:
1. A door lock, comprising a bolt mounted to swing into and out of locking position relative to the door casing, a locking lever normally engaging the said bolt to hold the latter in locking position, manually-controlled actuating means on a face of the door and adapted to impart a swinging motion to the said locking lever to unlock the said bolt, and a spring connected with the said bolt for retracting the same when unlocked.
  2. A door lock, comprising a bolt mounted to swing into and out of locking position relative to the door casing, a locking lever normally engaging the said bolt to hold the latter in locking position, an actuating member mounted to swing on a face of the door and engaging the said lever to swing the latter into release position relative to the said bolt on exerting pressure on the said actuating member, and a spring connected with the said bolt for retracting the same when released by the said lever.
  3. A door lock, comprising a bolt mounted to swing into and out of locking position relative to the door casing, a locking lever normally engaging the said bolt to hold the latter in locking position, a door knob 50 mounted to slide transversely on a face of the door and having a lug engaging the said locking lever to swing the latter into release position relative to the said bolt on exerting a pull on the door knob, and a spring connected with the said bolt for retracting the same when the said lever is swung into release position.
  4. A door lock, comprising a bolt mounted to swing into and out of locking position relative to the door casing, a locking lever normally engaging the said bolt to hold the latter in locking position, an actuating member mounted to swing on a face of the door and engaging the said lever to swing the latter into release position relative to the said bolt on exerting a pull on the door knob, and a spring connected with the said bolt for retracting the same when the said lever is swung into release position.
  5. A lock, comprising a keeper located in the door jamb and provided with bolt-opening means comprising pivoted and spring-pressed members having sidewise extending pins, a casing located in the door, a locking bolt mounted to swing in the casing and provided with cams adapted to be engaged by the pins of said bolt opening means to engage the bolt with the keeper on closing the door, a locking lever fulcrumed in the casing and normally engaging the said bolt to hold the latter in locked position, and manually-controlled actuating means on a face of the door and adapted to engage the said locking lever to swing the latter into release position relative to the said bolt.
  6. A door lock comprising a keeper, spring-pressed arms fulcrumed at one end 90 in the keeper, a lock casing, and a bolt mounted to swing laterally in the said casing, the said spring-pressed arms being provided with means for engaging the said bolt to swing the bolt into engagement with the said keeper on closing the door.
  7. A door lock, comprising a keeper, a bolt opening member held in the said keeper, a lock casing, a bolt mounted to swing laterally in the said casing and adapted to be 100 engaged by the said bolt-opening member to swing the bolt into engagement with the said keeper on closing the door, a spring for retracting the said bolt, a spring-pressed locking lever fulcrumed in the casing and engaging the said bolt to hold the latter in either locked or unlocked position, and an arm mounted to swing transversely in a vertical plane on one face of the door and having a transverse member engaging the 110 said locking lever.
  8. A door lock, comprising a keeper, a bolt opening member held in the said keeper, a lock casing, a bolt mounted to swing laterally in the said casing and adapted to be 115 engaged by the said bolt-opening member to swing the bolt into engagement with the said keeper on closing the door, a spring for retracting the said bolt, a spring-pressed locking lever fulcrumed in the casing and engaging the said bolt to hold the latter in either locked or unlocked position, an arm mounted to swing transversely in a vertical plane on one face of the door and having a transverse member engaging the said locking lever, and a knob slidable transversely on the other face of the door and having a lug engaging the said locking lever independently of the said arm member.
  9. A door lock, comprising a keeper, a 130

bolt opening member held in the said keeper, a lock casing, a bolt mounted to swing laterally in the said casing and adapted to be engaged by the said bolt-opening member to 5 swing the bolt into engagement with the said keeper on closing the door, a spring for retracting the said bolt, a spring-pressed locking lever fulcrumed in the casing and engaging the said bolt to hold the latter in 10 either locked or unlocked position, an arm mounted to swing transversely in a vertical plane on one face of the door and having a transverse member engaging the said locking lever, and manually-controlled means 15 on the other face of the door and adapted to engage the said arm member to lock the arm against transverse swinging motion.

10. A door lock, comprising a bolt mounted to swing into and out of locking position 20 relative to the door casing, a locking lever normally engaging the said bolt to hold the latter in locking position, an actuating member mounted to swing on a face of the door and engaging the said lever to swing 25 the latter into release position relative to

the said bolt on exerting pressure on the said actuating member, and a key-controlled locking mechanism for the said actuating member.

11. A door lock, comprising a bolt mounted 30 to swing into and out of locking position relative to the door casing, a spring connected with the bolt and tending to hold the same out of locking position, a locking lever normally engaging the said bolt to 35 hold the latter in locking position, a door knob mounted to slide transversely on a face of the door and having a lug engaging the said locking lever to swing the latter into release position relative to the said bolt 40 on exerting a pull on the door knob, and a key-controlled locking mechanism for the said door knob.

In testimony whereof I have signed my name to this specification in the presence of 45 two subscribing witnesses.

MARK FRED RICHARDSON.
